UNITED STATES PATENT OFFICE

2,553,457

DROP END GONDOLA CAR

Orville Ingram, Washington, D. C.

Application February 14, 1946, Serial No. 647,609

6 Claims. (Cl. 105—406)

1

My invention relates to railway freight cars and more particularly to gondola cars having drop end doors which, being disposed in an upright position when closed, are movable in opposition to the action of gravity upon being moved from open to closed position.

Drop end doors of gondola cars commonly weigh about 850 pounds apiece. Considerable difficulty is, therefore, usually experienced in moving the doors upwardly from their horizontal positions to their closed vertical positions. Two or more workmen are customarily required to effect closure of these doors or else some mechanical means, such, for example, as a crane, which is not often available, must be employed.

The principal object of the invention is to provide simple and reliable mechanism capable of practical application to the drop end door of a railway gondola car for imparting to the door, whose swinging movement from open position to closed position is opposed by the action of gravity, a force generated by the opening movement of the door itself which tends to force the door toward closed position and is of sufficient magnitude to enable a single workman to move the door from open to closed position.

A primary feature of the invention consists in employing a single torsion rod which is energized upon an opening movement of the door to provide a force tending to return it to closed position, one end of the rod being immovably held in a bracket secured to one corner of the door and the opposite end of the rod being immovably held in a bracket secured to the car body adjacent the opposite side of the door.

Another feature of the invention consists in providing the drop end door with a pair of brackets at the lower corners thereof, one of which is provided with a pintle rotatably mounted in a bracket carried by the car body and the other of which is formed with a hub portion rotatably mounted on the floor of the car.

A further feature of the invention consists in providing the drop end door with brackets secured adjacent the lower corners thereof, a torsion rod being immovably held in one of the brackets and extending through an opening in the other of said brackets for attachment to the car body so that the rod is energized upon an opening movement of the door to provide a force tending to return it to closed position.

Other and more specific features of the invention, residing in advantageous forms, combinations and relations of parts, will hereinafter appear and be pointed out in the claims.

2

In the drawings,

Figure 1 is a vertical transverse sectional view of a railway gondola car showing the lower portion of a drop end door provided with the invention.

Figure 2 is an enlarged fragmentary sectional view taken on line 2—2 of Figure 1.

Figures 3 and 4 are enlarged sectional views taken on lines 3—3 and 4—4 of Figure 2.

Figure 5 is a side view, as viewed from the right, of the bracket secured to the lower right hand corner of the drop end door shown in Figure 1.

Figure 6 is a front view of the bracket shown in Figure 5.

Figure 7 is an enlarged view taken on line 7—7 of Figure 1, omitting the car floor and other parts of the car.

Figure 8 is a side view, as viewed from the left, of the bracket secured to the lower left hand corner of the door.

Figure 9 is a front view of the bracket shown in Figure 8, a portion of the bracket through which the torsion rod extends being broken away.

Figure 10 is a sectional view taken on line 10—10 of Figure 1, the car floor and other adjacent portions of the car being omitted.

Figure 11 is a side view of the car bracket illustrated in Figure 10, as viewed from the right side thereof, the securing bolt being omitted.

Figure 12 is a sectional view of the car bracket taken on line 12—12 of Figure 10.

Figure 13 is a plan view of one of the halves of the bushing which is inserted in the door bracket illustrated in Figure 9.

Figure 14 is a front view of the half of the bushing illustrated in Figure 13, as viewed from the left of that figure.

Figure 15 is an end view of the half of the bushing illustrated in Figure 13.

Figure 16 is a view corresponding to Figure 14 of the other half of the bushing.

Figure 17 is a view similar to Figure 15 of the other half of the bushing.

Referring more particularly to the drawings, 1 indicates the drop end door of a railway gondola car having sides 2, and a floor 3. The under-frame of the car which may be of any usual and well known construction is not illustrated nor is the upper portion of the car and of the drop end door, as these parts may be of any suitable construction and form no part of the present invention. The floor 3 may be advantageously formed of metal plates welded to the side walls 50 or side sheets of the car as indicated in Figure 1.

Secured to the lower corners of the door are brackets 4 and 5 respectively, each of which includes a plate portion 6 secured to the main body portion of the door and a flange portion 7 secured to the inclined and relatively inwardly offset lower portions of inturned marginal flanges 8 of the door.

The lower portion of bracket 4 on the door is provided with a recess 9 which may conveniently be polygonal in cross section so as to receive the correspondingly shaped end of a torsion rod 10 which extends transversely of the door adjacent its lower edge. This recess is preferably formed so that its axis coincides with the axis of a hinge pintle 11 which projects outwardly from the bracket for reception in an upwardly opening recess 12 in the adjacent one of the two brackets 13 and 14 respectively secured to the car body.

The lower portion of the recess 12 is more or less cylindrically curved and it is preferably provided with a pair of upstanding legs or arms 15, the upper portions of which are apertured to receive a bolt 16 to close the recess and prevent accidental displacement of the pintle 11 therefrom. As small particles of lading frequently get under the bottom of the door and also between the lower edge thereof and the adjacent part of the car, the bolt 16 is placed a substantial distance above the pintle and the recess 12 is purposely made larger than the pintle so that the adjacent lower portion of the door may readily shift to adjust itself to existing conditions.

The bracket 5 secured to the opposite corner of the door is formed with a hub portion 17 which rests upon and engages a substantially Z-shaped wear plate 18 when the door is being moved from one position of closure to the other as well as when it is disposed in either position of closure. As may be seen from Figures 3 and 4, the wear plate has a substantially horizontal web 19, with which the hub 17 is engageable, constituting an extension of the car floor. Extending downwardly from the inner edge of the web 19 is a flange 20 and extending upwardly from its outer edge is an upstanding flange 21 which is interposed between the door 1 and the end sill 22. In addition to the abutment for the door afforded by the upstanding flange 21 of the wear plate, additional abutments are provided by inside corner posts 23, each having a flange 24 secured to the adjacent side sheet and a flange 25 which is adapted to overlap the outer face of the door. Backing up the flanges 25 of the inside corner posts are outside corner posts 26 which may be of any desired construction and are preferably secured to the flange 25 of the inside corner posts.

The aperture in the hub of bracket 5 is of such size that the adjacent polygonal end of the torsion rod 10 may pass therethrough and be secured to the bracket 14 on the car after the torsion rod has been inserted through the aperture in bracket 5. A bushing 27 may be conveniently inserted within the aperture to reduce the size thereof and thereby prevent undue lateral movement of the torsion rod when it is twisted as a result of movement of the door. The opening in the bushing through which the torsion rod extends is, however, of greater diameter than the rod, as seen in Figures 1 and 4, so that, should lading unintentionally become lodged under or in back of the hinged edge of the door, the door may nevertheless shift slightly to accommodate itself to the lading and yet the bushing will not bear

on the rod with such force as to prevent swing-ing movement of the door.

The bushing may advantageously be made in two identical separable parts so that it may be placed within the aperture in the bracket 5 after the torsion rod is positioned therein. The abutting faces of the two parts of the bushing are, in the main, disposed at substantially a 45° angle with respect to the walls thereof, but they are also formed with abutting faces 28 substantially parallel with the adjacent walls of the sections. To prevent the bushing from turning within the aperture of bracket 5, the sections thereof are respectively provided with lugs or projections 29 adapted to fit within correspondingly shaped recesses in the walls bounding the aperture in the bracket.

The bracket 14 on the car to which one end of the torsion rod is immovably secured is advantageously formed with an upwardly opening recess 30 having inclined walls or sides 31 which are spaced apart a distance just slightly greater than the thickness of the cooperating polygonal end of the torsion rod. Moreover, the base of the recess is at substantially 90° with respect to the inner faces of the inclined walls 31 in order that the cooperating adjacent polygonal end of the rod which may advantageously be four sided, is immovably held within the recess 30. At the lower corners of the recess, the bracket is preferably formed with wall portions 32 which are adapted to overlap the inner face of the polygonal end of the rod and thus prevent it from being disconnected therefrom upon axial movement thereof, and in Figure 10 one of the walls 32 has been broken away to permit the lowest corner of the polygonal end of the rod and recess to be seen.

Like bracket 13, bracket 14 is also provided with a removable bolt 33 adapted to bridge the space between the inclined walls 31 of the recess and thereby prevent accidental displacement of the torsion rod therefrom. The walls of the recess 30 are inclined relatively to the walls of the recess 9 in bracket 4 at the opposite side of the door so that the rod may be placed under initial torsion and thereby afford a greater force tending to return the door to closed position than if the rod were otherwise initially installed. This initial twisting of the rod may be accomplished by either first securing bracket 4 to the door or by first securing bracket 14 to the car body after the polygonal ends of the torsion rod have been suitably placed within the recesses of the brackets. However, it has been found more convenient to first secure the brackets 4 and 5 to the door and then, after the torsion rod has been assembled therewith and with the car bracket 14 and during the operation of riveting the bracket to the car sides, to forcibly move the bracket 14 into the position indicated in the drawings thus imparting the desired twist to the rod.

The torsion rod may advantageously be enclosed and thus protected from lading within the car by a cover plate 34. At its lower end, it is welded to the inner end of a bottom marginal flange 35 of the door and by being suitably bent the cover plate is secured at its upper end to the main body portion of the door. The car brackets 4 and 5 are each provided with inwardly extending lugs 36 or the like for engaging the inner face of the cover plate 34 to maintain it in spaced relation to the torsion rod.

In the operation of the device, it will be appreciated that, since one end of the rod is im-

movably held by one of the door brackets and the other end is immovably held by the car bracket adjacent the opposite side of the door, opening or inward movement of the door will subject the rod to torsion which will provide a force tending to return it to upright or closed position. The force exerted by the torsion rod is sufficiently great that the door may be easily closed by a single workman.

Various modifications may be made in the structural details of the embodiment of the invention disclosed without departing from the spirit of the invention as defined in the appended claims.

What I claim is:

1. Door mechanism for a hinged drop end door of a railway gondola car involving brackets secured to the lower corners of the door, brackets secured to the car body between the side walls of the car and the opposite sides of the door, the brackets on the car being spaced transversely of the car from the brackets on the door, and a torsion rod extending transversely of the door adjacent its lower edge connected to one of the brackets on the door and having its other end connected to the bracket secured to the car body adjacent the opposite side of the car, the other one of said brackets on the door having a portion provided with an opening through which said torsion rod extends, said portion of the bracket loosely encircling the rod, said door being movable transversely of its hinge axis so that the lower edge of the door will accommodate itself to lading remaining in the car to thereby enable the door to swing from closed to open position.

2. Door mechanism for a hinged drop end door of a railway gondola car involving brackets respectively secured to the lower corners of the door, brackets secured to the car body adjacent opposite sides of the door and respectively spaced laterally from the brackets on the door, one of said brackets on the door having a hub portion rotatably supported on the car floor and said hub being provided with a substantially centrally disposed opening, and a torsion rod extending transversely of the door adjacent its lower edge, one end of said torsion rod extending through said opening and being secured to the bracket on the car body adjacent thereto and the opposite end of said rod being secured to the bracket on the door at the opposite side corner thereof the portion of the rod disposed within said opening being of less size than the opening so as to permit the lower edge of the door to move transversely of its hinge axis and thereby accommodate itself to lading remaining in the car.

3. Door mechanism for a hinged drop end door of a railway gondola car involving brackets respectively secured to the lower corners of the door, brackets secured to the car body respectively adjacent opposite sides of the door, the brackets on the car being spaced transversely of the car from the respectively adjacent brackets on the door, means hingedly connecting one of the brackets on the door and the adjacent bracket on the car, a rod extending transversely of the door adjacent the lower edge thereof having polygonal ends of greater cross sectional area than the rod, one end of the rod being secured to the bracket on the door which is hingedly connected to the bracket on the car and the other of said brackets on the door having an opening to permit the polygonal end on the opposite end of the rod to pass therethrough, the last men-

tioned polygonal end of the rod being secured to the adjacent bracket on the car body whereby said rod is energized upon an opening movement of the door to provide a force tending to return it to closed position, said means and said opening in one of the door brackets permitting the lower edge of the door to move transversely of its hinge axis to accommodate itself to lading remaining in the car to thereby enable free swinging movement of the door.

4. Door mechanism for a hinged drop end door of a railway gondola car involving brackets respectively secured to the lower corners of the door, brackets secured to the car body respectively adjacent opposite sides of the door and disposed laterally thereof, one of the brackets on the door being in engagement with the floor and having an opening therethrough, the other of said brackets on the door having a recess and pivotally connected to the adjacent bracket on the car in spaced relation with the car floor, and a torsion rod having one end immovably secured in said recess and having its opposite end extending through said opening in the door bracket at the opposite side of the door and immovably secured to the adjacent bracket on the car body whereby said rod is energized upon an opening movement of the door to provide a force tending to return it to closed position said pivotal connection of said opening permitting movement of the lower edge of the door transversely of its hinge axis so that the door may accommodate itself to lading remaining in the car to thereby enable free swinging movement of the door.

5. Door mechanism for a hinged drop end door of a railway gondola car involving brackets respectively secured to the lower corners of the door, brackets secured to the car body between the side walls of the car and the opposite sides of the door and spaced laterally from the brackets on the door, one of the brackets on the door having a projecting hinge pintle loosely mounted in the adjacent bracket on the car, and a single torsion rod extending transversely of the door adjacent the bottom edge thereof and having its axis substantially parallel with the axis of said pintle, one end of said rod being immovably secured to the door bracket having said pintle and the opposite end of said rod loosely extending through an opening in the other door bracket and being immovably secured to the adjacent bracket on the car so that said rod will be energized upon an opening movement of the door to provide a force tending to return it to closed position, said pintle and said opening permitting the lower edge of the door to move transversely of its hinge axis so that it may accommodate itself to lading remaining in the car to thereby enable free swinging movement of the door.

6. Door mechanism for a hinged drop end door of a railway gondola car involving brackets respectively secured to the lower corners of the door, brackets respectively secured to the car body between the side walls thereof and the opposite sides of the door, a torsion rod extending transversely of the door adjacent the lower edge thereof having polygonal ends of greater cross sectional area than the cross sectional area of the rod, a polygonal recess in one of the brackets secured to the car body for receiving and holding against rotation one end of said torsion rod, the adjacent bracket on the door having a portion formed with an opening loosely encircling said rod, and a polygonal recess in the bracket on the door adjacent the opposite side thereof for

receiving and holding against rotation the opposite end of said rod, said last named bracket on the door having a hinge pintle loosely mounted in the said bracket secured to the car body adjacent thereto said pintle and said opening permitting the lower edge of said door to move transversely of its hinge axis so that the door may accommodate itself to lading remaining in the car to thereby permit free swinging movement of the door.
